(57) **CLAIM**

The ornamental design for caregiver and child burp protection cover up, as shown and described.

DESCRIPTION

FIG. 1 is a front perspective view of a caregiver and child burp protection cover up showing my new design in use;

FIG. 2 is a rear perspective view thereof;

FIG. 3 is a side perspective view thereof;

FIG. 4 is a top plan view showing the design laid flat and fastened;

FIG. 5 is a top plan view showing the design laid flat and unfastened; and,

FIG. 6 is a bottom plan view thereof.

In FIGS. 1-3 the broken lines representing human figures show the design in use and form no part of the claimed design. The remaining broken lines on the surface of the cover up represent stitching.
